UNITED STATES PATENT OFFICE

154,957

DESIGN FOR A CALENDAR OR THE LIKE

Walter F. Rothe, Washington, D. C.

Application October 7, 1947, Serial No. 141,789

Term of patent 14 years

(Cl. D74—5)

To all whom it may concern:

Be it known that I, Walter F. Rothe, a citizen of the United States of America, residing in Washington, District of Columbia, have invented a new, original, and ornamental Design for a Calendar or the like, of which the following is a specification, reference being had to the accompanying drawing, forming part thereof.

The figure is a front view of a calendar or the like showing my new design.

The article is of no appreciable or substantial thickness.

I claim:

The ornamental design for a calendar or the like, substantially as shown and described.

WALTER F. ROTHE.
